 stadt, near Berlin, Germany

Application July 8, 1935, Serial No. 30,378
 In Germany July 13, 1934

10 Claims. (Cl. 179—18)

The present invention relates to telephone systems with main and subsidiary exchanges and automatic operation and the object is to produce a system which will enable connections to be set up between subscribers of the same subsidiary exchange (internal calls) in a more simple and positive manner.

This is achieved in that two speaking lines are provided between the main and subsidiary exchanges, of which one is provided in the subsidiary exchange with a double purpose selector used for exchange calls and for the outgoing connecting path for internal calls, and the second with a final selector for use with internal calls.

It is particularly advantageous for a telephone system to enable internal calls in a subsidiary exchange to be set up without unnecessarily withdrawing the local connecting lines within the main exchange from traffic or necessitating the dialling of a special characterizing number.

This is attained according to the invention in that a characterizing selector is associated in the main exchange with a connecting line running between the main and subsidiary exchanges, which, corresponding to the number of impulses of an impulse train determining the desired call direction, either prepares the influencing of subsequent selectors in the main exchange used for setting up exchange calls, or initiates the establishment of an internal call over a selector of the subsidiary exchange.

In Figs. 1 and 2 a system with a main and subsidiary exchange is illustrated as an embodiment of the invention, while Figs. 3, 4, and 5 are a modification thereof. The arrangement illustrated in Figs. 1 and 2 in addition to the outgoing and incoming calls enables connections to be set up between subscribers of the same subsidiary exchange. For this purpose, in addition to selector DB30 which serves for setting up outgoing and incoming calls (exchange calls) and thus works as a double purpose selector, a second selector LW30 is provided in the subsidiary exchange which serves to set up internal connections within the subsidiary exchange. This auxiliary selector is connected over an auxiliary line (a2, b2) between the subsidiary exchange and main exchange to the connecting line leading to the main exchange which is seized by calling subscribers.

In order to differentiate between the different call directions i. e. outgoing exchange calls and internal calls, an additional switching device is provided (magnet Di30, wipers dI30—dIV30)

in the main exchange which is switched round according to the characterizing number dialled so that either a call is set up over the connecting devices of the main exchange, or the auxiliary selector LW30 in the subsidiary exchange can be set on the desired subscriber's connection. In the present embodiment the characterizing is arranged so that by dialling the digit 1 an outgoing call is characterized, while by dialling the subscriber's number directly, i. e., any digit except 1 an internal call and thereupon the subscriber desired in the internal call, is characterized.

The characterizing digit for the outgoing exchange call is not taken up by the connecting devices in the main exchange, but only by the characterizing switching device and the auxiliary selector LW30 provided in the subsidiary exchange.

In the normal condition of the system all of the selectors in the subsidiary exchange and also the switching devices in the main exchange and in addition all the relays, are uninfluenced.

Outgoing calls

When a subscriber takes up his receiver and momentarily depresses the key, for example key B2 in the case of subscriber A2, earth is connected to lead a1 of the connecting line leading to the main exchange. In the main exchange relay X30 energizes over the circuit: earth, battery, resistance Wi9, wiper dII30, winding I of relay X30, contacts 345x30, 348an30, 350c30, lead a1, winding I of relay U31, wiper a1 of selector DB30 in position O, key B2, earth. Relay X30 locks up over its winding II on closing its contact 373x30. Contact 345x30 disconnects battery from the lead a1 of the connecting line. Contact 331x30, however, connects battery to the b1 lead. The following circuit is then set up: earth, magnet W31, contact 309u31, b1 lead of the connecting line, contacts 335c30, 337x30, 339e30, 342y30, relay K30, battery, earth. In this circuit the magnet W31 energizes in the subsidiary exchange and relay K30 in the main exchange, so that selector DB30 in the subsidiary exchange advances one step. Similarly the switching device influenced by the magnet D30 in the main exchange is advanced one step, after this magnet has been energized over contact 316k30. On the energizing of this magnet, contact 318d30 is closed and thus relay Y30 is switched on over resistance Wi24. This relay opens its contact 342y30, among others, so that the operating circuit of magnet W31 and relay

K30 is broken, so that these are both deenergized. By the opening of contact 316k30 magnet d30 is also deenergized which again results in the opening of contact 318d30 and hence the de-energizing of relay Y30. Contact 342y30 is again closed and thereby the operating circuit for magnet W31 and for relay K30 is set up afresh, so that selector DB30 in the subsidiary exchange and the switching device in the main exchange which is influenced by relay K30, advance a further step.

Since the calling subscriber A2 is connected to the second contact of selector DB30, on reaching this contact, after relay Y30 has operated as before after the completion of the second switching step, the following circuit is set up: earth, battery, relay P30, contacts 347y30, 346x30, 348an30, 350c30, lead a1 of the connecting line, winding I of relay U31, wiper a1 of selector DB30 in position 2, subscriber A2, wiper b1 of the same selector in position 2, winding II of relay U31, contacts 307u31, 306w32 (1-17) (mechanically operated by LW30), earth. It should be noticed that the connection of the testing relay P30 to lead a1 by relay Y30 takes place after each step of the switching device in the main exchange. By the closing of contact 319p30 relay Y30 is held energized so that by the opening of contact 342y30 further transmission of impulses for advancing the switching device is prevented. Earth is connected to lead b1 over contact 340y30 and the choke Dr31, so that after opening contact 307u31 and closing contact 308u31 the following locking circuit is set up for relay U31, energized in the above testing circuit: earth, choke coil Dr31, contacts 341k30, 340y30, wiper dIV30 in position 1-11, contact 335c30, lead b1 of the connecting line, contact 308u31, winding II of relay U31, wiper b1 of selector DB30 in position 2, subscriber A2, wiper a1 of selector DB30 in position 2, winding I of relay U31, lead a1 of the connecting line, contacts 350c30, 348an30, 346x30, 347y30, relay P30, battery, earth. At contact 354p30 a loop is closed for the connecting devices of the main exchange so that, just as in the case of a subscriber having an individual line, preselecting device, for example a call finder, is set in operation. After the setting of such a preselecting device, if the calling subscriber is connected to a free connecting device he receives a signal from the exchange.

Since it is an outgoing call which is being set up in the present case, the subscriber must dial the characterizing digit 1. It should be added that relay J30 was energized over contacts 324x30 and 326p30 and also over wiper dIII30 in position 0, so that contact 354p30 which was closed by the testing relay P30 which operates as the impulse relay during the numerical selection, is shunted by contact 355j30. The selection of the characterizing digit 1 is accordingly not transmitted to the connecting devices of the main exchange. On the first impulse, i. e. on the first deenergizing of relay P30, the magnet d30 of the characterizing switching device is operated in the main exchange over contacts 324x30, 327p30 and 328j30, and relay V30 is operated in parallel with the magnet; moreover, by the transitory closing of contact 375p30, battery is connected over contact 374j30 to the b2 lead of the auxiliary connecting line and hence magnet W32 of the auxiliary selector LW30 is operated. By means of relay V30, energized during the impulse emission, the choke coil Dr30 is short circuited by the closing of contact 352v30, and by

the opening of contacts 351v30 and 353v30 the condensers in the speaking leads are disconnected so as to ensure a more clear impulse emission. After the one impulse has been given relay V30 deenergizes on account of the prolonged opening of contact 327p30, so that relay J30, which after one step has been made can hold up over wiper dIII30 in position 1 and over contact 325v30, is deenergized. The short circuit of impulse contact 354p30 is accordingly removed by the opening of contact 355j30 so that the next impulse trains can be transmitted to the connecting devices of the main exchange. The magnet W32 in the subsidiary exchange, which previously displaced the auxiliary selector LW30 one step, can no longer be effected since the corresponding impulse circuit is broken at contact 374j30.

When the desired subscriber is reached, after testing on the contact in the normal way, ringing current is transmitted and the speaking connection is established on the desired subscriber replying. When the conversation has finished a metering impulse is transmitted to the c-lead in any desired manner which does not concern us here. This is extended to the meter SM2 in the main exchange corresponding to the calling subscriber of the subsidiary exchange. The connecting of the corresponding meter takes place on the setting of selector DB30 in the subsidiary exchange by the switching device in the main exchange controlling this selector.

By the switching on of winding II of relay Y30 in the c-lead, which relay assists in sending out the control impulses, the existing connection is prevented from being released during this metering even when the calling subscriber replaces his receiver and thereby releases relay P30 which lies in the circuit of speaking current. When the metering is completed and the calling subscriber replaces his receiver relays P30 and U31 deenergize. Since a locking circuit no longer exists for relay Y30 in the c-lead it is disconnected by the opening of contact 319p30 so that it deenergizes. At contacts 342y30 and 309u31 the operating circuit through magnet W31 and relay K30 in series is now closed again, so that now, in the same way as for the setting of selector DB30 on the calling subscriber, this is again controlled synchronously by the switching device in the main exchange. If the selector DB30 thus moves on to a subscriber's line in which the subscriber has just taken up the receiver, seizing can at once take place again, since both the selector in the subsidiary exchange and the switching device in the main exchange are both in the same switching position, so that the meter in the main exchange corresponding to the calling subscriber is also connected up when the switches are brought to rest. If such a call does not occur, a selector DB30 and the controlling switching device in the main exchange accordingly reach position 11, relay E30 energizes in the main exchange over: earth, battery, relay E30, wiper dIII30 in position 11, contact 324x30, earth. Relay E30 establishes a locking circuit for itself over its contact 363e30. The operating circuit passing over the b1 lead is broken by contact 339e30, and also battery is connected to lead b2 of the auxiliary connecting line, so that now magnet W32 of selector LW30 which stands in position 1 is influenced in series with relay K30 of the main exchange. The impulse circuit previously operating magnet D30 is correspondingly opened at contact 312e30 and is

switched over to magnet D_{i30} of the characterizing selector by the closing of contact $313e30$. The auxiliary selector LW_{30} is accordingly switched on one step, and through the energizing of relay K_{30} in the same circuit magnet D_{i30} is operated over contact $316k30$, and likewise advances the characterizing selector one step. Relay Y_{30} is operated by the closing of contact $317d_{i30}$, and by opening contact $342y_{30}$ breaks the operating circuit for the magnet W_{32} and relay K_{30} . Contact $316k_{30}$ is accordingly opened, so that by the disconnection of magnet D_{i30} and the associated opening of contact $317d_{i30}$, relay Y_{30} is deenergized and the operating circuit for magnet W_{32} and relay K_{30} is again closed. This alternating play is repeated until the characterizing switching device has reached position II . When this occurs relay H_{30} is operated over wiper $d130$ and contact $367y_{30}$, and hence contact $314h_{30}$ is opened which now breaks the impulse circuit for magnet D_{i30} and connects relay Y_{30} directly in this impulse circuit. Relay K_{30} deenergizes on the opening of contact $372h_{30}$. The auxiliary selector LW_{30} is moved on further by means of impulses from the main exchange, but there the characterizing switching device does not move with it. The switching device LW_{30} continues to be advanced until it reaches position II . In this position earth is connected to the lead $a2$ over wiper $a2$ of the switching device LW_{30} . Thus relay U_{32} is energized in the following circuit: earth, wiper $a2$ of switching device LW_{30} in position II , winding I of relay U_{32} , lead $a2$ of the connecting line, contact $344h_{30}$, resistance W_{i19} , battery, earth. By the opening of contact $302u_{32}$ the switching magnet W_{32} is disconnected and also the circuit of relay K_{30} is broken. The current is cut off from relay Y_{30} by the opening of contact $316k_{30}$ so that this relay opens contact $367y_{30}$ and deenergizes relay H_{30} . Contact $344h_{30}$ is opened and the energizing circuit of relay U_{32} described above is broken down. Contact $302u_{32}$ again closes the operating circuit for magnet W_{32} and relay K_{30} , so that selector LW_{30} in the subsidiary exchange advances one step and likewise the magnet D_{i30} energized over contact $316k_{30}$ advances the characterizing switching device in the main exchange by one step. Accordingly both switching devices accomplish the last step into the normal position together. In the position 0 of wiper $d130$ relay E_{30} remains energized over contacts $364h_{30}$ and $365e_{30}$ until, since relay Y_{30} is energized over contact $317d_{i30}$ through the last switching step, relay H_{30} is again energized over: earth, wiper $d130$ in position 0 , contacts $365e_{30}$, $368x_{30}$, $367y_{30}$, relay H_{30} , battery, earth. By the opening of contact $364h_{30}$ the locking circuit for relay E_{30} is broken and this relay therefore deenergizes. Relay H_{30} holds up, after the opening of contact $365e_{30}$ over contact $371h_{30}$. After contact $317d_{i30}$ has opened relay Y_{30} again deenergizes. By the closing of contact $399e_{30}$ relay K_{30} is furthermore again connected to the $b1$ lead of the connecting line and also preparation is made for switching in the magnet D_{30} of the switching device in the main exchange in the impulse circuit already described, over contact $312e_{30}$. Thereupon only magnet W_{31} is operated in series with relay K_{30} . The latter causes relay Y_{30} to energize over contact $316k_{30}$, so that this opens the energizing circuit of magnet W_{31} by opening contact $342y_{30}$. By the alternate play of these relays the switching magnet is influenced until

the selector DB_{30} reaches position II . In this position the following circuit is set up: earth wiper $a1$ of selector DB_{30} in position II , winding I of relay U_{31} , lead $a1$ of the connecting line, contacts $350c_{30}$, $348an_{30}$, $345x_{30}$, $344h_{30}$, resistance W_{i19} , battery, earth. Relay U_{31} energizes and by opening contact $309u_{31}$ disconnects the magnet W_{31} . Relays K_{30} and Y_{30} then also release so that now relay H_{30} is deenergized by the opening of contact $367v_{30}$. Through the closing of contact $314h_{30}$ the switching magnet D_{30} in the main exchange is connected up while the energizing circuit just described for relay U_{31} is broken down at contact $344h_{30}$. The operating circuit for magnet W_{31} and relay K_{30} is accordingly closed again at contact $309u_{31}$. The selector DB_{30} is thus advanced one step and moves into the normal position. At the same time magnet D_{30} is also influenced by the closing of contact $316h_{30}$ so that the switching device in the main exchange similarly makes one switching step which takes it into the normal position. Since the wiper dIV_{30} of this switching device has now left contact segments $I-II$ further advancement of the switching device is not possible. All the devices both in the subsidiary and also in the main exchange are now again in the normal position.

Incoming traffic

30

If a subscriber of the subsidiary exchange, for example A_2 is called from the main exchange a final selector, which is not shown, is set by the corresponding numerical selection. If the connecting line leading to the subsidiary exchange is already seized the wiper $d130$ is not in the normal position, so that the final selector cannot test over the c -lead ($c2$) corresponding to the desired subscriber. The wiper $d130$ remains away from the normal position as long as any of the switching devices of the connecting line either in the main exchange or in the subsidiary exchange are displaced from the normal position. Seizing the connecting line over a final selector is only possible when all these switching devices have reached the normal position. In the present case the final selector tests over the lead $c2$ corresponding to the subscriber A_2 . The circuit passes over resistance W_{i20} , contact $358an_{30}$, relay An_{30} , wiper $d130$ in position 0 , contact $360an_{30}$, resistance W_{i22} , battery, earth. Relay An_{30} energizes in this circuit and locks up independently of wiper $d130$ over contact $359an_{30}$. At contact $348an_{30}$ battery is disconnected from the $a1$ lead of the connecting line, so that no seizure of the connecting line can take place from the subsidiary exchange. At contact $336an_{30}$ battery is connected to lead $b1$ of the connecting line through relay K_{30} . The following circuit is thus set up: earth, magnet W_{31} , contact $309u_{31}$, lead $b1$ of the connecting line, contacts $335c_{30}$, $336an_{30}$, $339e_{30}$, $342y_{30}$, relay K_{30} , battery, earth. By the alternate play between magnet W_{31} and the magnet D_{30} in the main exchange operated by relays K_{30} or Y_{30} (as described in the case of outgoing traffic), the selector DB_{30} in the subsidiary exchange is now advanced synchronously with the switching device in the main exchange operated by magnet D_{30} . This advancement is continued until the wiper $d130$ has reached the lead $c2$ seized by the final selector. At this moment the selector DB_{30} has also reached the second contact, to which subscriber A_2 is connected. When this occurs relay C_{30} tests over contact $361an_{30}$ and by opening

75

contact **335c30** prevents both the switching devices mentioned from being further advanced. At contacts **334c30** and **349c30** the speaking leads of the connecting line are switched over on to the speaking leads of the final selector. Relay **An30** now holds up over contact **357c30**. Ringing current can now be sent from the final selector, which is not shown, to the desired subscriber **A2** of the subsidiary exchange in the known way.

When the desired subscriber replies the ringing current is disconnected in the final selector in any manner with which we are not now concerned. Relay **U31** is operated over the subscriber's loop by the feeding current connected in the final selector, so that the **b1** lead of the connecting line is switched through at contact **308u31**, and magnet **W31** is disconnected at contact **309u31**. The subscriber **A2** is now connected to the final selector of the main exchange just as a normal subscriber having an individual line.

When the conversation has finished the **c2** lead is disconnected in the final selector, relay **C30** being thus deenergized. Contacts **334c30** and **349c30** open and break the circuit for the feeding current, so that relay **U31** deenergizes. One effect of this is that the operating circuit for magnet **W31** and relay **K30** is closed through the closing of contact **309u31**. Through the alternate play of the corresponding relays the selector **DB30** in the subsidiary exchange is advanced synchronously with the switching device in the main exchange. Thus, in the same way as was explained in the case of outgoing traffic, the selector in the subsidiary station is first advanced synchronously with the switching device in the main exchange until position **11** is reached. Then it is moved on as far as position **17** alone by means of impulses from the main station, whereupon it completes the final step into the normal position together with the switching device of the main exchange. During the release motion of the switching devices seizing cannot take place again until the two switching devices have returned to the normal position, since, in the case of an incoming call, relay **X30** which takes up the initiation of a call is otherwise not energized.

Internal calls

Seizing of the connecting line leading to the main exchange by the calling subscriber attached to the subsidiary exchange takes place in the same way as has already been described in the case of outgoing traffic. While in the case of outgoing traffic (exchange calls) the subscriber had to dial the characterizing digit 1, in the case of internal calls he must now dial the number which the desired subscriber has for internal calls, immediately. Since the digit 1 is employed for outgoing traffic, the internal numbers of the subscribers are limited to the numbers 2 to 10. Thus in this case 9 subscribers can be attached to the subsidiary exchange.

As described above, relays **J30** and **V30** are energized during the dialling, while relay **P30** is intermittently deenergized by the impulses, so that if for example, the calling subscriber **A2** desires a connection to subscriber **A3** and accordingly dials the digit 3, magnet **W32** receives three impulses over the lead **b2** and contacts **374j30** and **375p30** (impulse contact). The auxiliary selector **LW30** is thus set on the third contact. The characterizing switching device is advanced synchronously by its magnet **D30** to the third contact. After the dialling relay **V30** is deenergized,

relay **Z30** is influenced over: earth, battery, relay **Z30**, contact **366z30**, wiper **dII30** in position 3, earth. Since the impulse contact **354p30** in the main exchange loop is shunted during the dialling, by contact **355j30**, the connecting devices of the main exchange are not set. By the opening of contact **356z30** the preselecting device in the main exchange is now no longer seized. Since relay **J30** remains energized over: earth, contacts **320y30**, **322j30**, **321p31**, wiper **dIII30**, relay **J30**, battery, earth, relay **R30** is operated over: earth, battery, relay **R30**, contacts **369j30**, **370z30**, 3 seconds switch. Subscriber **A3** is called by ringing current transmitted from the main exchange: ringing current source, contacts **330r30**, **332z30**, **333p30**, lead **a2** of the connecting line, winding I of relay **U32**, wiper **a2** of the auxiliary selector **LW30** in position 3, subscriber **A3**, wiper **b2** of the auxiliary selector **LW30** in position 3, winding II of relay **U32**, contact **303u32**, earth. Since relay **R30** is influenced over a 3 second switch ringing current is transmitted to the desired subscriber every 3 seconds. The calling subscriber receives part of this ringing current as a "free" signal over contact **310r30**.

If the desired subscriber replies within a pause in the ringing i. e. at a moment when relay **R30** is deenergized the following circuit is set up: earth, contact **303u32**, winding II of relay **U32**, wiper **b2** of the auxiliary selector **LW30** in position 3, subscriber **A3**, wiper **a2** of the auxiliary selector **LW30** in position 3, winding I of relay **U32**, lead **a2** of the connecting line, contacts **333p30**, **332z30**, **331r30**, winding I of relay **P31**, battery, earth. In this circuit relays **P31** and **U32** energize. Since contact **303u32** is opened on the energizing of relay **U32**, the earth necessary for holding relays **U32** and **P31** energized is connected through contact **311p31** and winding II of relay **P31**, after the lead **b2** of the connecting line has been switched through. Meanwhile relay **J30** is deenergized by the opening of contact **321p31** and relay **R30** is deenergized by the opening of contact **369j30**, so that further transmission of ringing current is prevented. The feeding current for both subscribers is supplied from the main exchange. For subscriber **A2** the circuit runs from the battery connected to lead **a1** and relay **P30**, to the earth connected through the choke coil **Dr31** and lead **b1**, while for subscriber **A3** current is fed from the battery connected through winding I of relay **P31** to lead **a2** of the connecting line, to the earth connected through winding II of relay **P31** to lead **b2**.

Metering of internal calls takes place by the meter **SM2** of the calling subscriber **A2**, connected through the switching device of the main exchange (wiper **dII30**) being influenced over contacts **362z30**, **323j30**, **320y30**, and earth.

On the termination of the conversation, when the calling subscriber replaces his receiver relays **P30** and **U31** deenergize. Contact **319p30** opens and the relay **Y30** is thus deenergized, while by the opening of contact **333p30** relay **P31** is deenergized. By the closing of contact **342y30** battery is connected to the **b1** lead of the connecting line over relay **K30**, so that the magnet **W31** of selector **DB30** in the subsidiary exchange is energized. By the alternate play which has already been described above, the selector of the subsidiary exchange is advanced synchronously with the switching devices of the main exchange so that both switching devices are stepped round as far as position **11**. In position **11** relay **E30** again energizes and causes the auxiliary selector **LW30**

in the subsidiary exchange to be advanced in the manner already described, under the influence of the corresponding magnet W_{32} . The characterizing switching device is switched on together with this selector. When these two switching devices reach the normal position by the switching operations described above, the selector DB_{30} of the subsidiary exchange is moved on automatically under the control of relays K_{30} and Y_{30} in the main exchange until it reaches position 11. It then completes the final switching step into the normal position together with the switching device in the main exchange.

This short description of the release motion should suffice, since a detailed description has already been given of the release in the case of an outgoing call.

If the called subscriber of an internal call does not reply, relay P_{30} releases when the calling subscriber replaces his receiver, while relay J_{30} is only released after the release of relay Y_{30} . Accordingly the earth is disconnected from the metering circuit by contact $320y_{30}$ before contact $353z_{30}$ closes so that in this case metering does not take place.

Special circuits

If selector DB_{30} in the subsidiary exchange is displaced from the normal position by hand, earth is connected over contact $301w_{31}$ to lead a_2 over wiper a_2 of the auxiliary selector LW_{30} , so that relay X_{30} is energized in the main exchange and locks up over contact $313x_{30}$. Battery is connected to the b_1 lead over contact $337x_{30}$ and thus the magnet W_{31} in the subsidiary exchange is influenced in series with relay K_{30} in the main exchange. The selector DB_{30} is now held until magnet D_{30} in the main exchange has been switched on through the closing of contact $316k_{30}$ whereupon both switching devices are advanced synchronously as in the case of a subscriber's call, until they reach position 11. In this position relay E_{30} energizes, as in the case above, and causes the auxiliary selector LW_{30} in the subsidiary exchange and the characterizing selector (rotary magnet D_i) to advance synchronously to position 11, whereupon the auxiliary selector continues to advance alone into position 17 in precisely the same way as in the case of the release of an outgoing call, the last step into the normal position being executed together with the characterizing switching device. After this selector DB_{30} is advanced into position 17 and then finally into the normal position the last step being made together with the switching device of the main exchange, if the magnet W_{32} of the auxiliary selector is displaced from the normal position by hand, contact $305w_{32}$ (1-17) connects earth over the wiper a_1 of the selector DB_{30} to the a_1 lead of the connecting line, so that relay X_{30} is again influenced. In a manner corresponding to that above, selector DB_{30} and the switching device in the main exchange which is operated by magnet D_{30} , are again advanced, whereupon after reaching position 11, the magnet W_{32} of auxiliary selector LW_{30} is influenced synchronously with the characterizing switching device D_{i30} . The release motion thus takes the same course as is described above. If both selectors in the subsidiary exchange are displaced from the normal position simultaneously, then since contacts 0 and 1 are connected together in the auxiliary selector, earth is connected to the a_2 lead of the connecting line over contact $301w_{31}$,

so that again relay X_{30} is operated and the release motion described above takes place.

If the switching device in the main exchange which is operated by magnet D_{30} is displaced from the normal position by hand, battery is connected to lead b_1 over wiper dIV_{30} , and hence the selector DB_{30} in the subsidiary exchange and the switching device in the main exchange are advanced by the known interaction. All other operations take place as above. In contrast with the movements described above, the connecting line cannot be seized during this return motion, because relay X_{30} , which prepares a circuit for the testing relay P_{30} , is not energized. If the characterizing switching device which is operated by magnet D_{i30} is displaced by hand from the normal position, relay E_{30} energizes over wiper dIV_{30} , and through contact $338e_{30}$ completes a circuit for magnet W_{32} in the subsidiary exchange and relay K_{30} in the main exchange, so that now the characterizing switching device in the main exchange and the auxiliary selector LW_{30} in the subsidiary exchange are advanced synchronously by the interaction as above. If, for example, at this moment seizing takes place on the part of the final selector in the main exchange, relays A_{30} and C_{30} can be energized but the selector DB_{30} in the subsidiary exchange can only be set when the characterizing selector D_{i30} is in the normal position, so that relay E_{30} releases and by closing contact $339e_{30}$ connects battery to the b_1 lead of the connecting line. Each seizure is indicated by the lighting up of the seizing lamp L . Seizing can also be recorded. If seizing in the incoming and outgoing directions is to be recorded separately the contacts $312h_{30}$ and $311an_{30}$ can be led separately to a recording device.

In Figures 3, 4, and 5, a modified system with main and subsidiary exchanges is illustrated as an embodiment of the invention, Fig. 3 showing the devices arranged in the subsidiary exchange, and Figs. 4 and 5 those in the main exchange. The switching arrangements of the system enable the establishment of outgoing and incoming calls (exchange calls) and also of internal calls. In order to be able to set up these calls, in addition to the selector DB_{40} which serves as a call finder for outgoing calls and as a final selector for incoming calls, an auxiliary selector LW_{40} is provided in the subsidiary exchange which is used as a final selector on setting up internal calls. This selector is in connection with the main exchange over a special connecting line and is there connected to the connecting line seized by the calling subscriber when an internal call is set up. The differentiation between outgoing calls (exchange calls) and internal calls results from dialling special characterizing numbers which so operate a characterizing switch in the main exchange that this switch is operated from the normal position by each impulse train.

Outgoing traffic

When the subscriber A_1 removes his receiver and operates key B_1 the following circuit is set up: earth, key B_1 , wiper a_1 of selector DB_{40} , winding I of relay U_{41} , lead a_1 of the connecting line, contacts $415c_{40}$, $419an_{40}$, $502x_{40}$, winding I of relay X_{40} , wiper dII in position 0, resistance 70 W_{31} , battery, earth. Relay X_{40} locks up over its contact $492x_{40}$. By closing contact $418x_{40}$ the following circuit is completed: earth, magnet W_{41} , contact $404u_{41}$, lead b_1 , contacts $413c_{40}$, $418x_{40}$, $432e_{40}$, $436y_{40}$, relay K_{40} , battery, earth. 75

- In this circuit the magnet **W41** and relay **K40** energize. The selector in the subsidiary exchange thus makes one switching step. By the closing of contact **440k40** magnet **D40** (wipers *di40*—*diIV40*) is also operated so that the selector in the subsidiary exchange and the switching device in the main exchange take one switching step synchronously. Relay **Y40** is switched on over contact **444d40** of magnet **D40** and interrupts 5 at contact **436y40** the energizing circuit for magnet **W41** passing over the *b*-lead. Moreover relay **K40** is also deenergized, so that by opening contact **440k40** magnet **D40** is also deenergized. By 10 the opening of contact **444d40** relay **Y40** is de-15 energized and thus a new energizing circuit is set up for magnet **W41** in the subsidiary exchange. Through the reenergizing of relay **K40** magnet **D40** is also now energized once more. The mutual interaction continues until the calling sub-20 scriber is reached through selector **DB40** in the subsidiary exchange. Since in the present case the calling subscriber is connected to the first contact, both the switching devices are only advanced one step. By the energizing of relay **Y40** 25 which occurs after each switching step relay **P40** is connected each time to lead *a1*, so that on reaching the calling subscriber the following circuit is set up: earth, battery, relay **P40**, contacts **504y40**, **503x40**, **419an40**, **415c40**, lead *a1* of the 30 connecting line, winding *I* of relay **U41**, wiper *a1* of selector **DB40** in position *I*, subscriber *A1*, wiper *b1* of selector **DB40** in position *I*, winding *II* of relay **U41**, contacts **402u41**, **400w42** (*I*—*II*), earth. By closing its contact **437p40** relay **P40** 35 holds relay **Y40** energized so that no further influencing of the switching device can occur. In the testing circuit described above relay **U41** also energizes in the subsidiary exchange and at contact **403u41** switches through the connecting line 40 to the main exchange, while through opening contact **404u41** magnet **W41** is disconnected. By the closing of contact **456p40** relay **J40** is energized. By the closing of contact **422p30** the loop 45 to the connecting devices in the main exchange is closed thus causing a connecting device to be seized by a pre-selector as in the case of an individual subscriber's call. When the calling subscriber receives dialling tone he can begin to dial.
- 50 On operating the dial, relay **P40** in the main exchange, which serves as a testing relay in setting selector **DB40**, is deenergized according to the impulses, whereupon the impulses are transmitted to the connecting devices of the main exchange through contact **422p40**. On the first deenergizing of relay **P40** relay **V40** is energized over contact **467p40** and holds up during the impulse train since it is a slow acting relay. The choke coil **Dr42** is short circuited by the closing 55 of contact **420v40** so that by the simultaneous disconnection of the condensers in the speaking leads by the opening of contacts **416v40** and **421v40** the impulse emission is maintained free from distortion. It should be noticed that 60 throughout the emission of the impulses relay **U41** in the subsidiary exchange and relay **Y40** in the main exchange are kept energized.
- 65 Until it has been established that an outgoing call is proceeding the characterizing switching device (wipers *di40*—*diIV40*) operated by the magnet **Di40** is operated in step with the setting of the connecting devices in the main exchange, magnet **Di40**, since during the impulse emission relay **J40** is kept energized over contact **446v40**, 70 being operated over the following circuit: earth,

battery, switching magnet **Di40**, contacts **459j40**, **458z40**, **457p40**, **455x40**, earth. If now, for example, the digit first dialled is different from the internal characterizing digit, relay **V40** deenergizes and opens contact **446v40** thus deenergizing relay **J40**, so that now relay **F40** is operated over wiper *diIV40* (earth, battery, relay **F40**, contacts **464h41**, **465j40**, wiper *diIV40* (*I*—*II*), earth). Contact **445j40** prevents relay **J40** being operated again when the next impulse train is 10 transmitted, so that the characterizing switching device is brought to rest.

The further impulses are extended in a similar way from relay **P40** through contact **422p40** to the connecting devices in the main exchange, 15 but now the characterizing switch in the main exchange is no longer influenced. After setting the connecting devices the desired subscriber may be rung by any desired means, with which we are not concerned, and conversation thus established.

On terminating the conversation a metering impulse is transmitted to the meter of the calling subscriber, which is connected up in the main exchange through wiper *diI40* of the 20 switching device in the main exchange which is moved synchronously with the selector **DB40** in the subsidiary exchange when the latter is set. During the metering impulse occurring over the *c*-lead the connection is maintained, even when 25 the calling subscriber replaces his receiver, in that relay **Y40** which is connected in the *c*-lead is maintained energized over its winding *II* during the metering. The circuit flowing over the *c*-lead is only broken after the metering has been completed. It may be broken in any desired way. Relay **Y40** thus can deenergize, and after the receiver has been replaced at the calling station, which causes relay **U41** to deenergize and hence 30 inter alia contact **404u41** to be closed, the following circuit, serving to advance selector **DB40** in the subsidiary exchange, is closed by the closing of contact **436y40**: earth, magnet **W41**, contact **404u41**, lead *b1* of the connecting line, contact **413c40**, wiper *diV40* in positions *I*—*II*, contacts **45432e40**, **436y40**, relay **K40**, battery, earth. Selector **DB40** in the subsidiary exchange makes one switching step and by the closing of contact **440k40** the magnet **D40** in the main exchange 35 is operated so that this switching device is also advanced one step. As in the case of setting up the connection of the calling subscriber with the main exchange, the switching device in the main exchange controls the switching device in the subsidiary exchange. Both advance to position 40 *I* under the influence of relays **K40** and **Y40**. In this position relay **E40** is operated over wiper *diII40* and contact **475x40**. By closing contact **431e40** relay **K40** is connected to lead *b2*, it being disconnected from lead *b1* by the opening of 45 contact **432e40**. By the opening of contact **433e40** the magnet **D40** is disconnected from the automatic impulse circuit, and the magnet **Di40** of the characterizing switching device is connected to the latter by the closing of contact **439e40**. The magnet **W42** of the auxiliary selector **LW40** is now energized over lead *b2*, whereupon relay **K40** is influenced simultaneously in the main exchange. The magnet **Di40** thus receives an impulse over contact **440k40** so that by 50 closing contact **443d40** relay **Y40** is energized and the advancing circuit for the auxiliary selector **LW40** in the subsidiary exchange is again opened at contact **436y40**. By this interaction 55

70 75 80 85 90 95 98

Incoming traffic

both switching devices are advanced synchronously to position 11. In this position relay H40 is now energized over: earth, wiper d140 in position 11, contact 476y40, relay H40, battery, earth.

5 By the opening of contact 493h40 winding I of relay X40 is disconnected, and by the opening of contact 441h40 the magnet D40 of the characterizing switch is disconnected from the automatic impulse circuit. The magnet W42 in the 10 subsidiary exchange is now operated alone, without the magnet D40 in the main exchange being operated, through the reciprocal play of relays K40 and Y40, in a corresponding way, until the wiper a2 in the subsidiary exchange reaches position 17. In this position earth is connected to the a2 lead, so that the following circuit is set up: earth, wiper a2 of auxiliary selector LW40 in position 17, winding I of relay U42, lead a2 of the connecting line, contact 505h40, resistance Wi34, 15 battery, earth. Relay U42 energizes and disconnects the magnet W42 at contact 410u42. This is associated with the deenergizing of relays K40 and Y40, so that by the opening of contact 476y40 relay H40 is deenergized. By the opening of contact 20 505h40 winding I of relay U42 is deenergized, and by the closing of contact 441h40 the magnet D40 of the characterizing switch is again connected to the circuit which is influenced by contact 440k40. The magnet W42 connected over 25 contact 410u42 is now operated, as is also the magnet D40 by way of relay K40, so that both switching devices make one switching step and thus move together into the normal position. Through relay Y40, which is operated after the 30 switching step over contact 443d140, relay H40 is again operated after the switching step has been taken over the circuit: earth, wiper d140 in position 0, contacts 447e40, 513x40, 476x40, relay H40, battery, earth. The locking circuit is 35 then completed over: earth, contacts 512h40, 476y40, relay H40, battery, earth. By the opening of contact 478h40 relay E40 is deenergized so that by contact 439e40 the magnet D40 is disconnected and thus the connection of magnet 40 D40 is prepared at contact 438e40. Then after the deenergizing of relay Y40 on account of the opening of contact 440k40 selector DB40 in the 45 subsidiary exchange is advanced into position 17, in that magnet E41 is energized in series with relay K40 over: earth, magnet W41, contact 406u41, lead b1, contact 413c40, wiper d140, contacts 432e40, 436z40, relay K40, battery, earth. Relay K40 again operates relay Y40 over contact 440k40, so that by the opening of contact 436y40 both 50 relay K40 and the magnet W41 are deenergized. Through this interaction the selector DB40 is thus advanced to position 17. In this position earth is connected to lead a1 over wiper a1, so that relay U41 energizes over this lead and by 55 opening contact 404U41 deenergizes the magnet W41 and relay K40. On account of contact 446k40 being held open relay Y40 is deenergized and hence also relay H40 (contact 476y40). By the closing of contact 441h40 magnet D40 is connected to the automatic impulse circuit. Meanwhile relay U41 is again deenergized by the opening of contact 505h40 so that over the b1 lead the selector DB40 in the subsidiary exchange takes the last switching step together with the switching device, which is operated by magnet D40. Since wiper d140 has now left the segment 11—17, further advancement is prevented. Only now can a new seizure of the connecting line take 60 place.

70

When the conversation has finished the c1 lead is cut off from the final selector in any desired way, so that relay C40 deenergizes. By opening contact 469c40 relay An40 is also deenergized. In the subsidiary exchange relay U41 is deenergized so that the magnet W41 is again connected to b1 lead of the connecting line over contact 404u41. The return of the switching devices to the normal position now takes place in the same way as has been described in the case of the release of outgoing traffic.

75

Internal calls

The seizure of the connecting line leading to the main exchange by the calling subscriber A1 is accomplished in the same way as has been de- 75

scribed for outgoing traffic. In order to reach a subscriber attached to the same subsidiary exchange the subscriber A1 must dial the complete normal number of this subscriber. In the present 5 example the number 2,419,572 is chosen as the number of the desired subscriber A2. As mentioned above, after connecting the calling subscriber A1 to the connecting line by the energized relay P40, relay J40 is energized over contact 10 456p40, wiper dIII40 in position 0 and contact 455x40, and holds up during the individual impulses over contact 466v40 of relay V40 which is energized during the impulses.

Subscriber A1 thus first sends out two impulses, 15 and hence by the operation of the corresponding contacts of relay P40, which previously operated as testing relay, magnet D40 (impulse contact 457p40) is energized twice and accordingly advances the corresponding switching device by two 20 switching steps while the seized connecting device of the main exchange likewise receives two impulses through contact 422p40. When relay V40 deenergizes at the end of the impulse train, relay J40 holds up over: earth, battery, relay J40, 25 contact 44540, wiper dIII40 in position 2, contacts 507h42, 453h43, 452h44, winding I of relay H41, earth. In this circuit H41 energizes and operates relay F40 over contact 463h41, and also locks up over its winding II by closing contact 30 466h41. By the closing of contact 462p40 magnet D40 receives an impulse, so that the characterizing switch takes one switching step. Hereupon magnet D40 opens its contact 461di40 so that relay F40 deenergizes. After the switching step 35 has been taken and magnet D40 is again deenergized by the opening of contact 462p40 so that contact 461di40 is again closed, relay F40 is again operated and causes the characterizing switch to be advanced again. This stepping is continued 40 until the characterizing switch has reached the zero position, since in this case wiper dIV40 has left the contact segment 1—11 and hence relay H41 is deenergized. Relay F40 is prevented from 45 energizing by the opening of contact 463h41. In the zero position of the characterizing switch relay J40 again energizes over wiper dIII40. This operation just described occurs during the pause 50 between two impulse trains. It may also be mentioned that in position 11 of wiper dIII40, during the advancement of the characterizing switch, relay H42 is operated and locks up over contacts 484h42, 489p41 and 490v40. Thus after the return of wiper dIII40 to position 0, relay U40 is 55 operated over contact 500h42, and is held in a locking circuit independently of wiper dIII40 by closing contact 497u40.

By dialling the second digit 4 the characterizing switch is brought to position 4. After the opening of contact 446v4 relay J40 holds up over: 60 earth, battery, relay J40, contact 44540, wiper dIII40 in position 4, contacts 506h42, 453h43, 452h44, winding I of relay H41, earth. Relay H41 energizes in this circuit, locks up over contact 466h41 and, as has been described above, causes the operation of the magnet D40 of the characterizing switch. This is then brought to the normal position by the alternate operation of relay F40. When wiper dIII40 again comes to position 11, relay H43 is operated over: earth, battery, relay H43, contacts 487h44, 514u40, wiper dIII40 in position 11, earth. By the closing of contact 488h43 relay H43 locks up. Relay U40 is deenergized by the opening of contact 501h43.

When the calling subscriber dials the third 75 digit which consists of one impulse, the charac-

terizing switch stands on the first contact after the train has passed. The following circuit is set up: earth, battery, relay J40, contact 44540, wiper dIII40 in position I, contacts 454743, 452h44, winding I of relay H41, earth. By the 5 energizing of relay H41 relay F40 is again operated and brings the characterizing switch into the zero position again. During this motion, when wiper dIII40 is in position 11, relay H44 is operated over: earth, battery, relay H44, contacts 482h43, 511h45, 508u40, wiper dII40 in position 11, earth. By closing contact H44 relay H44 completes a locking circuit for itself independent of wiper dIII40. In position 0 relay U40 is again operated over contacts 499h44, 498h45 and wiper dII40 in position 0 and locks up over contact 497u40.

In a similar manner, through the fourth impulse train (9 impulses), after relay H41 has been operated on the 9th step, relay H45 is energized 20 on the advancement of the characterizing switch into the normal position, by relay F40 in position 11, the circuit being: earth, battery, relay H45, contacts 485h44, 507u40, wiper dIII40 in position 11, earth. By the opening of contact 498h45 relay U40 is deenergized. The characterizing switch has again reached position 0.

After the fifth digit has been dialled, which consists of five impulses the characterizing switch stands on the fifth contact, so that after relay 30 H41 has energized in this switch position, relay F40 is again energized and the characterizing switch is returned to the zero position. During this motion relay H46 is energized over wiper dII40 in the following circuit: earth, wiper dII40 35 in position 11, contacts 508u40, 509h45, relay H46, battery, earth. By closing contact 480h46 this relay locks up. Meanwhile the characterizing switch reaches the zero position. After the dialling of the sixth digit which consists of seven 40 impulses and hence moves the characterizing switch round seven steps so that its wiper reaches position seven, relay Z40 is operated over: earth, battery, relay J40, contact 44540, wiper dIII40 in position 1, contact 447h46, winding I of relay 45 Z40, earth. By closing contact 468z40 relay Z40 locks up over its winding II. By the opening of contact 458z40 further influencing of the characterizing switch by numerical impulses is prevented. Moreover it cannot be brought back to 50 the normal position since relay H41 is not operated.

When the calling subscriber dials the last digit, in the present case the digit 2, since contact 429z40 is now closed this is transmitted, with the 55 help of contact 428p40 to magnet W42 over lead b2 and thus the auxiliary selector LW40 in the subsidiary exchange is set on the contact of the desired subscriber. The transmission of this impulse train to the connecting devices in the main 60 exchange is prevented in that contact 423z40 has opened the impulse circuit and moreover has thereby released the connecting devices in the main exchange. Relay R40 is brought under the influence of a switching device over contacts 496z40 and 49540 every three seconds, and is thereby energized, so that every three seconds 65 ringing current is transmitted to the desired subscriber over lead a2 by the closing of contact 425r40. The calling subscriber receives a portion 70 of this ringing current over contact 510r40 as an indication that the line is free.

When the called subscriber replies, relay P41 energizes in the ringing pause over: earth, battery, resistance W28, contacts 429z40, 421p40, 75

winding I of relay P41, contact 426r40, lead a2 of the connecting line, winding I of relay U42, wiper a2 of the auxiliary selector LW40 in position 2, subscriber A2, wiper b2 of the auxiliary selector 5 in position 2, winding II of relay U42, contact 408u42, earth. Through relay P41 relays H42 to H46 are deenergized on account of the opening of contact 489p41, so that by the opening of contact 447h46 relay J40 is also deenergized. Accordingly relay R40 cannot be further energized over contact 495j40, so that the transmission of ringing current is interrupted. In the circuit closed when the desired subscriber replies relay U42 energizes as well as relay P41 and by closing contact 15 409u42 switches lead b2 through to the main exchange. Both subscribers are connected together over contacts 411p41 and 424p41, and current is fed from the main exchange. For the calling subscriber the current passes over relay 20 P40 and the choke coil Dr41, and for the called subscriber over windings I and II of relay P41.

The internal call is metered in that the meter SM1 connected over wiper dIII40 corresponding to the movement of the switching device DB40 25 in the subsidiary exchange, is energized over contacts 471z40, 491j40 and 490y40 on the reply of the desired subscriber.

When, after ending the conversation, the calling subscriber replaces his receiver, relay P40 30 which is influenced over the subscriber's loop deenergizes. Thereupon relays Y40 and Z40 and also relay P41 are deenergized. Relays U41 and U42 also deenergize. By the closing of contacts 436y40 and 494u41 the operating circuit for the 35 magnet W41 in the subsidiary exchange and for relay K40 in the main exchange is closed, and thus the switching devices are released in a similar manner to that already described for the case of outgoing calls.

40 Had the desired subscriber not replied, relay Y40 and then relay Z40 would have deenergized when the calling subscriber replaced his receiver before contact 491j40 had been closed by the deenergization of relay J40, so that in this case no 45 metering would have taken place.

Special circuits

If the selector DB40 in the subsidiary exchange is displaced from the normal position by hand 50 earth is connected to the a2 lead over contact 405w41 and wiper a2 of the auxiliary selector LW40 in position 0, and hence relay X40 is energized in the main exchange, so that, as in the case of a subscriber's call, an operating circuit is completed over contact 418x40 for magnet W41 55 in the subsidiary exchange and for relay K40 in the main exchange. The selector DE40 in the subsidiary exchange is prevented from being released, by magnet W41 being held energized in 60 this circuit until relay K40 also influences magnet D40 in the normal way and so also advances this switching device by one step. Relay Y40 is then again cut off from the operating circuit as in the case of setting up an outgoing call, so that 65 the selector in the subsidiary exchange and the switching device in the main exchange are then advanced synchronously to position 11. In this position, as in the release motion for outgoing traffic, the magnet W42 is operated and brings 70 selector LW40 to the zero position with the characterizing switch Di40, whereupon selector DB40 is advanced to position 17 independently and then moves to the zero position together with the switching device controlled by magnet D40. 75

If the auxiliary selector LW40 is displaced from

the zero position by hand, earth is connected over contact 401w42 (1-17) to the zero position of wiper a1 of selector DE40, so that in this case, as in the case of a subscriber's call, relay X40 is influenced in the main exchange. In this case 5 also both switching devices rotate in the same way as has been described for the case of release. In order to prevent a subscriber, on removing his receiver, from causing the seizure of the connecting line, which in the case of dialling an internal call must result in a wrong selection since the auxiliary switch LW40 is displaced, earth is cut off from contact 402u41 by contact 400w42 (1-17), so that the testing relay P40 in the main exchange cannot test on the subscriber's contact. 10 15

If both switching devices in the subsidiary exchange are displaced from the normal position by hand, earth is again connected to the a2 lead so as to energize relay X40, over contact 407u41, since obviously relay X40 must be energized for 20 every release of the switching devices in the subsidiary exchange because otherwise no control of these can take place over the main exchange. In this case also the earth is disconnected through contact 400w42 (1-17). 25

Thus as soon as the synchronism between the switching devices in the subsidiary exchange and the switching devices in the main exchange is destroyed, setting on a calling subscriber is no longer possible. 30

If the switching device in the main exchange operated by magnet D40 is displaced from the normal position by hand the operating circuit for magnet W41 and relay K40 over lead b1 of the connecting line is completed over wiper dIV40 35 in positions 1-11, so that the switching devices return to the zero position as above described. Seizure of the connecting line by a subscriber who removes his receiver at this moment cannot occur because relay X40 is not energized and accordingly the testing relay P40 is not connected to lead a1 of the connecting line. 40

If on the other hand the characterizing switch is displaced from the zero position by hand, relay E40 energizes over wiper dIV40 positions 1-11, 45 and connects a negative potential to lead b2 of the connecting line through contact 431e40 and relay K40, whereby magnet E42 is energized as well as relay K40. Both switching devices are then brought to the zero position synchronously, 50 as described above. Since relay E40 is energized during this motion, even if relay X40 is energized due to a new call occurring during this motion, the selector DB40 in the subsidiary exchange can only be set after the return to the normal position, since for the moment contact 432e40 is still 55 open.

In the main exchange each seizure of the connecting line can be indicated by the lighting of the seizing lamp L. They can also be recorded 60 by a special device. If it is desired to record incoming and outgoing seizures separately the contacts 492x40 and 494an40 can each be connected separately to a recording device. 65

Having described the invention, what is considered to be new and is desired to be protected by Letters Patent will be set forth in the following claims.

What is claimed is:

1. In an automatic telephone system, a main 70 and a subsidiary exchange, a pair of trunk lines extending between said exchanges, a selector switch in one of the trunk lines operated to establish calls between the subsidiary and the main exchange and also operated to prepare a con- 75

- necting path for local calls between two subscribers in the subsidiary exchange, and another selector switch in the other of said trunk lines operated to complete said local calls over a path 5 including both of said trunk lines.
2. In an automatic telephone system, a main and a subsidiary exchange, a pair of trunk lines connecting said exchanges together, a separate selector switch in each of said trunk lines at the 10 subsidiary exchange, means for operating one of said selector switches to establish a call from the subsidiary to the main exchange over the trunk line associated with said selector switch, means for operating the other one of said selector 15 switches to establish an internal call in the subsidiary exchange including the trunk line associated with said other selector switch, said first switch and its associated trunk line also operated to provide a connecting path for said local call.
- 20 3. In an automatic telephone system, a main and a subsidiary exchange, two trunk lines connecting said exchanges, a selector switch in each of said trunk lines at the subsidiary exchange, means for operating one of said switches for extending calls between said exchanges including only the trunk line associated with the selector switch, means for operating the other of said selector switches for extending calls local in the subsidiary exchange including the associated 25 trunk line, said first selector switch also operated to provide an outgoing path over its associated trunk line for the local calls.
4. In an automatic telephone system, a main and a subsidiary exchange, two trunk lines connecting said exchanges together, a selector switch at the subsidiary exchange in each of the trunk lines, means for extending calls between said exchanges over one of said trunk lines and its associated selector switch, and means for completing calls between calling and called subscribers in said subsidiary exchange over both of said trunk lines and both of said selector switches. 30
5. In an automatic telephone system, a main and a subsidiary exchange, two trunk lines connecting said exchanges together, a selector switch at the subsidiary exchange in each of said trunk lines, means for establishing calls between said exchanges over one of said trunk lines and its associated selector switch, means for establishing 35 local calls in the subsidiary exchange over both of said trunk lines and both of said selector switches, and means in said main exchange for connecting said two trunk lines together when a local called subscriber in the subsidiary exchange 40 answers.
6. In an automatic telephone system as claimed in claim 4, switching means in said main exchange connected to said trunk lines, said switching means controlling the operation of 45 both of said selector switches.
7. In an automatic telephone system as claimed in claim 4, a driving magnet for each of said selector switches, and a single control relay for each of said driving magnets connected in the 50 associated trunk line.
8. In an automatic telephone system, a main and a subsidiary exchange, a pair of trunk lines 55 extending between said exchanges, a selector switch at the subsidiary exchange in each of said trunk lines, a characterizing selector at the main exchange associated with one of said trunk lines, means controlled by a calling subscriber in the subsidiary exchange for transmitting impulses to establish a connection to the main exchange over one of said trunk lines and its associated selector or for establishing a connection with another local subscriber in the subsidiary exchange 60 extending over both of said selector switches and their associated trunk lines, and means controlled by said characterizing selector as determined by the impulses transmitted by a calling subsidiary subscriber for preparing the further extension of a call in the main exchange or for operating the selector switch in the other of said trunk lines to extend the call to another local subscriber in the subsidiary exchange.
9. In an automatic telephone system, a main and a subsidiary exchange, two trunk lines connecting said exchanges together, a selector switch in each trunk line at the subsidiary exchange, a characterizing selector at the main exchange associated with the first of said trunk lines, means 65 controlled by a calling subsidiary subscriber for transmitting a particular series of impulses over said first trunk line to extend a call to another subscriber in the main exchange, means responsive to a different series of impulses transmitted by the calling subscriber to extend a local call to another local subscriber in the subsidiary exchange including both of said trunk lines, said characterizing selector operated responsive to the inter-exchange call to control the further extension of the connection and responsive to a local call to control the selector switch in the second of said trunk lines, an impulse repeating contact in the circuit for further extending the inter-exchange call, and means for preventing the 70 further extension of a call by short-circuiting said contact on local calls and removing the short circuit by transmitting a particular series of impulses characterizing an inter-exchange call.
10. In an automatic telephone system, a main and a subsidiary exchange, two trunk lines connecting said exchanges, a selector switch in each trunk line at the subsidiary exchange, a characterizing selector switch at the main exchange associated with the first of said trunk lines, means 75 for establishing exchange calls from a subsidiary exchange subscriber to a subscriber in the main exchange over a connection including said first trunk line and associated selector, means for establishing local calls from one subsidiary subscriber to another over a connection including both of said trunk lines and their associated selector switches, means controlled by said characterizing selector switch for determining whether the call is to be extended to a local subscriber or main exchange subscriber, the establishment of the local and exchange calls being controlled by the transmission of series of impulses from the calling subscriber, and an impulse relay in the main exchange controlled by the impulse 80 series for completing the calls.

EDUARD WOCHINGER.
